UNITED STATES PATENT OFFICE

ALBERT HUPP, OF CHICAGO, ILLINOIS, ASSIGNOR TO STORMVISION CORPORATION,
A CORPORATION OF ILLINOIS

CLEAR-VISION DEVICE

Application filed May 9, 1928. Serial No. 276,354.

The main objects of this invention are to provide means for giving a clear vision under adverse atmospheric conditions, for drivers of vehicles, railway engines, motor boats and the like.

On railways great difficulty is met in providing means for enabling the engineer to see the road ahead and especially the signals in stormy weather and in sleet and snow. Heretofore it has been necessary in some cases to use peep holes which afford a clear vision, but expose the engineer to the weather.

In my invention I provide a disc which is rotated at very high speed. In tests under actual service conditions it has been shown that the rain, steam, sleet or snow cannot cloud the vision through the disc as long as the disc is revolving. The disc may be used directly for a window, or may be placed over the windows already provided. In a railway engine, the glass disc is rotatably mounted in a frame which is hinged to the frame of the cab window so that the device can be swung out of the way when desired, as in cleaning

the window.

Other objects and advantages are to provide a clear vision, rotating disc which is mounted at the margins so that the center of the disc is unobstructed; to provide such a device in which the parts can be made at low cost; to provide frictionless bearings which are well protected; to provide a device which presents a smooth surface to the weather, with the moving joints well shielded from moisture and dirt; and to provide such a device which may be driven by vacuum, or the compressed air from the engine supply under the control of a suitable throttling valve to regulate the speed; and to provide a mounting in which the disc is partially supported by the air pressure.

In the accompanying drawings is shown a device embodying my invention, which device is more particularly adapted for use in connection with the cab window of a locomotive or automotive vehicle; in which:

Figure 1 is a view of the clear vision device in position, looking from the front.

Fig. 2 is a plan sectional view of the same, taken on the line 2—2 of Fig. 1.

Fig. 3 is a detail view of the lower portion of the disc, with parts broken away and parts shown in section.

Fig. 4 is a vertical section through the device, taken on the line 4—4 of Fig. 1.

Fig. 5 is a side elevation of Fig. 1.

Fig. 6 is an enlarged section, taken on the line 6—6 of Fig. 1.

Referring to the drawings, the glass disc 1 is rotatably mounted in the circular frame 2, which is hinged at one side to the frame 3 of the cab window 4.

The disc is provided with a sash ring 5 which is provided with an inner annular recess 6 in which the disc 1 is held by means of the clamp ring 7, the clamp ring being secured to the sash ring by means of the screws 8. Suitable soft packing 9 is placed around the edge of the disc 1 to prevent the glass from rattling.

The frame 2 has an outstanding flange 10 which extends around the circular aperture in which the disc is mounted, and the sash ring 5 is annularly recessed around the edge and provided with a marginal flange 11 which extends over and covers the frame flange 10.

On the inner side of the frame flange is provided an annular groove 12 in which the ball bearings 14 are seated, the balls being preferably arranged in groups to avoid weight and are held in spaced relation by means of pockets in the ball retainer ring 15.

On the inner side, the balls are engaged between the sash ring and the clamp ring, the edges of the rings being chamfered so that they bear on either side of the balls. In the mounting just described, the ring is easily balanced in the ball bearing support, and the space for the balls can be closely regulated by adjusting the clamp ring retainer screws 8 so as to give freedom for movement without too much play. Also the disc and the balls can be readily taken out by removing the clamp ring. The frame ring 2 is riveted to the swinging leaf of the strap hinge 16, the body of the hinge being countersunk in the supporting frame member and secured thereto by the through bolts 116. The frame swings over the window and rests against the frame member 41 on the opposite side of the win-

dow, and strips of felt 17 are inserted above and below, between the frame and the window glass 4. The felt strips may be cemented, either to the frame or to the window glass, and serve to keep the moisture and dirt out from under the disc 1. The swinging edge of the frame is clamped in place by means of the toe bolts 18, which engage the edge of the frame and extend through the frame 41 of the window. The bolts are removably secured by the nuts 19 which are threaded onto the bolts on the inner side of the window.

For driving the disc, a groove 20 is provided in the periphery of the sash ring, the groove having suitable blades or ratchet teeth 21 contained therein for catching the air. The air pressure nozzle 22 is fixedly mounted on the window frame 41 by means of the clamp 23, and the outer end of the nozzle is flattened as shown in section in Fig. 4 so as to cover a segmental portion of the groove 20. The edge of the ring 2 and the lower filler 17 are cut away as shown to allow them to swing out away from the nozzle.

The nozzle is provided with a suitable valve 25 which is preferably located within the cab where it is convenient for the engineer for controlling the speed of the disc and a connection is made by suitable pipes to the compressed air reservoirs of the engine. By locating the end of the nozzle on the under side of the disc, the weight of the disc is partially carried by the pressure of the air, and the disc rotates with very little friction. For starting the moisture to move away from the center of the disc, the glass strips 28 may be used. These strips are secured to the surface of the disc at the center by transparent cement and the strips become invisible when the disc is revolving.

By mounting the disc at the edges, the center of the disc, which is also the center of the vision, is left unobstructed. The frame parts can be made almost entirely by stamping processes; the bearings and joints are well protected; and the outer surface of the device is smooth and does not offer any obstructions for collecting moisture and dirt.

Having thus described my invention, I claim:

1. In a clear vision device, a rotatably mounted transparent plate, means for rotating the plate at high speed, and a transparent strip secured to the center of the plate for propelling the moisture therefrom.

2. In combination in a clear vision device, a frame having a circular aperture, a transparent disc rotatably mounted in the aperture, and means for applying air pressure at the lower edge of the disc to rotate the disc at a high speed and to partially support the disc.

3. In combination in a clear vision device, a frame having a circular flange having an annular recess, a sash ring, a glass disc seated

in the sash ring, a clamp ring secured to the sash ring for holding the disc in place, and bearing balls engaged in said recess between said rings and the flange.

4. In combination in a clear vision device, a frame having a circular flange having an annular recess, a sash ring fitting over the flange, a glass disc seated in the sash ring, a clamp ring screwed to the sash ring for holding the disc in place, and a series of bearing balls engaged in said recess between the two rings and the flange so that the clearance for the balls can be determined by adjusting the clamp ring.

5. In a clear vision device, a frame having a circular aperture and an outwardly projecting flange around the aperture, a glass disc, and a ring frame for the disc, and bearing balls engaged between the ring frame and the flange, the ring frame having an inwardly projecting flange enclosing the frame flange.

6. In a clear vision device, a frame having a circular aperture, a glass disc having a marginal frame rotatably mounted over the aperture on said frame, and a nozzle for directing compressed air against the lower edge of the marginal frame of the disc so that the disc is rotated at high speed and the disc is also partially supported by the force of the air flowing from the nozzle.

Signed at Chicago this fifth day of May, 1928.

ALBERT HUPP.
